UNITED STATES PATENT OFFICE

115,250

DESIGN FOR A FINGER RING

John L. Crumpton, Durham, N. C.

Application April 3, 1939, Serial No. 84,003

Term of patent 7 years

To all whom it may concern:

Be it known that I, John L. Crumpton, a citizen of the United States, residing at Durham, in the county of Durham and State of North Carolina, have invented a new, original, and ornamental Design for Finger Rings, of which the following is a specification, reference being had to the accompanying drawing, forming part thereof.

Fig. 1 is a top plan view of the finger ring showing my new design.

Fig. 2 is a side elevation of the same.

I claim:

The ornamental design for a finger ring, as shown.

JOHN L. CRUMPTON.
